UNITED STATES PATENT OFFICE.

ERLE R. SHEPPARD, OF BALTIMORE, MARYLAND.

DESIGN FOR A BADGE OR EMBLEM.

No. 38,964.

Specification for Design.

Patented Dec. 31, 1907.

Application filed November 25, 1907. Serial No. 403,831. Term of patent 7 years.

To all whom it may concern:

Be it known that I, ERLE R. SHEPPARD, a citizen of the United States, residing at Baltimore, in the State of Maryland, have invented a new, original, and ornamental Design for Badges or Emblems, of which the following is a specification, reference being had to the accompanying drawing, forming part thereof.

The figure is a plan view of a badge or emblem, showing my new design.

I claim:

The ornamental design for a badge or emblem as shown.

ERLE R. SHEPPARD.

Witnesses:

LEE A. SHEPPARD,
IDA W. SHEPPARD.
